SNOW PLOW

Douglas W. Anderson, Palatine, Ill., assignor to Gilson Brothers Company, Fredonia, Wis., a corporation of Wisconsin

Application November 24, 1958, Serial No. 53,500

Term of patent 14 years

(Cl. D40—1)

Fig. 1 is a perspective view of a snow plow embodying my new design.

Fig. 2 is a side elevational view of the snow plow shown in Fig. 1, with the broken line portion omitted.

Fig. 3 is an opposite side elevation of the snow plow shown in Fig. 1, with the broken line portion omitted.

Fig. 4 is a rear elevation of the snow plow of Fig. 1 with the broken line portion omitted.

I claim:

The ornamental design for a snow plow, as shown and described.
